UNITED STATES PATENT OFFICE

WILLIAM E. MORSE, OF RAPID CITY, SOUTH DAKOTA

SURGICAL INSTRUMENT

Application filed November 7, 1929. Serial No. 405,459.

My invention relates to improvements in surgical instruments, and it consists in the combinations, constructions, and arrangements herein described and claimed.

An object of my invention is to provide a surgical instrument of the type employed for making blood transfusions in which novel means is provided whereby the blood is caused to pass in a continuous stream from the donor to the recipient.

A further object is to provide a device of the type described in which means is provided whereby a maximum amount of blood may be transferred within a minimum amount of time and in which the cooperating parts are so arranged that the device may be easily and quickly disassembled for cleaning, repairing, and the like.

Other objects and advantages will appear in the following specification, and the novel features of the invention will be particularly pointed out in the appended claims.

My invention is illustrated in the accompanying drawings, forming part of this application, in which

Figure 1 is a side elevation of a portion of my device.

Figure 2 is a top plan view, partly in section, of my invention.

Figure 3 is a sectional view taken along the line 3—3 of Figure 2.

Figure 4 is a sectional view taken along the line 4—4 of Figure 5, and

Figure 5 is a top plan view of a portion of one of the valves.

In carrying out my invention, I make use of a base plate 1 upon which upright supporting members 2, 3, 4, and 5 are mounted. The members 2, 3, and 4 are preferably fixed upon the base by any suitable means, such as welding or bolting. The member 5 is provided with a base portion 6 having a slot 7 therein. The support 5 may be adjusted and rigidly secured upon the base plate 1 by means of a thumb screw 8. The latter is disposed upon a threaded shank 9 associated with a lug 10 which is fixed upon the base plate 1. The lug 10, as will be seen from Figure 2, acts as a guide for the support 5. The members 2 and 5 are re-

cessed at 11 and 12. The members 3 and 4 are provided with recesses 13 and 14 conforming to the diameter of tubular projections 15 associated with caps 16 and 17. Each of the caps is provided with a threaded sleeve 18.

In referring to Figure 2, it will be noted that the sleeves 18 are disposed upon the ends of barrels 19 and 20. The caps have threaded relation with respect to the sleeves and may be removed therefrom. The sleeves are fixed upon the ends of the barrels 19 and 20. The latter are preferably formed from glass or other suitable transparent material. The opposite ends of the barrels are provided with caps 21 and 22. Each of the barrels is provided with a filler portion 23. The caps 21 and 22 support the outer ends of the barrels 19 and 20 within the recesses 11 and 12, respectively. The tubular members 15 support the opposite ends of the barrels upon the supporting members 3 and 4.

The barrels 19 and 20 are provided with plungers 24 and 25, respectively. The plunger 24 is fixed upon the end of a tubular plunger rod 26. The opposite end of the plunger rod is fixed within an opening 27 in a valve body 28. The valve body is provided with an opening 29 which is diametrically opposed to the opening 27 for receiving one end of a plunger rod 30. The end of the plunger rod 30 is rigidly secured within the opening 29. The openings in the tubular projections 15 are slightly larger than the diameters of the plunger rods 26 and 30 for permitting air to readily pass into and out of the barrels 19 and 20 during the movement of the plungers therein.

The valve body 28 is provided with a pair of diametrically opposed openings 31 and 32 within which connecting members 33 and 34, respectively, are disposed. An inlet tube 35 is associated with the connecting member 33 and an outlet tube 36 is associated with the connecting member 34. The inlet tube is provided with a valve 37 having connecting members 38 and 39. A tube 40 is disposed upon the connecting member 38 and a tube 41 is disposed upon the member 39. The tube 40 is provided with a hollow needle 42.

Hollow needles such as this are well known in the art and therefore require no detailed description. The valve 37 is provided with a handle 43 whereby the valve may be manipulated for placing the tube 40 in communication with the tube 35 or the latter with the tube 41. The purpose of this construction will be defined more fully later.

In Figure 2 I have also shown the tube 36 as being provided with a valve 44. This valve is provided with connecting members 45 and 46 for receiving tubes 47 and 48, respectively. The tube 47 is provided with a hollow needle 49. The tube 36 may be placed in communication with the tube 47 or the tube 48 by manipulating the handle 50 associated with the valve 44. The base plate 1 is provided with a pair of guide members 51 and 52 between which the lower end of the valve body 28 is disposed.

Referring now to Figure 4, it will be noted that the valve body is provided with a rotatable member 53 having grooves 54 and 55 therein. The inner end of the member 53 is provided with an opening within which a threaded shank 56 associated with a disc 57 is disposed. The inner end of the member 53 is also provided with a rectangular projection 58 which is preferably disposed within a similar opening in a washer 59. The disc 57 is provided with a plurality of openings between which ball bearings 60 are placed. It will thus be seen that the washer 59 provides a backing for the ball bearings 60 and holds the latter in operative engagement with the surface of the base plate 1.

The movable member 53 is provided with a slot 61 within which an actuating handle 62 is mounted. The end of the handle is secured to the member 53 by means of a pin 63. The handle may be moved from the full line position shown in Figure 5 to the dotted line position, whereby the device may be operated from either side, as will be more clearly defined.

From the foregoing description of the various parts of the device, the operation thereof may be readily understood. Preparatory to making a blood transfusion, let us say that the needle 42 is inserted into a vein in the body of the donor and that the needle 49 is similarly inserted into a vein in the body of the recipient. At this time the valves 37 and 44 are arranged in the positions shown in full lines. Let us assume that the handle 62 is positioned for operation upon the side of the device shown in Figure 5. In operation, the handle is grasped and moved, let us say, from right to left as viewed in Figure 5, at which time the member 53 will be moved sufficiently far to bring the groove 54 into a position for placing the tube 35 and the plunger rod 26 into communication. The valve body 28 is provided with a recess 64 whereby a pin 65 which is secured to the member 53 will engage

a shoulder 66 or 67 for limiting the distance through which the member 53 is rotated.

When the handle is moved from right to left, the first result is a rotation of the member 53, after which the member 53 is locked against rotation, and continued pressure from right to left upon the handle will cause a movement of the plungers 24 and 25. Such movement will cause blood to flow into the barrel 19 by reason of the suction created therein. When the plungers have been moved their entire distance, the handle 62 is moved from left to right, which results in the member 53 being moved for placing the grooves 54 and 55 in a position shown in Figure 2. Thus it will be seen that the blood within the barrel 19 will be forced therefrom into the tube 36 and finally through the needle 49. Simultaneously, the barrel 20 will be filled with blood which, upon reversing the movement of the plungers, will be forced through the tube 36 and the needle 49. By reason of this construction I have provided a device in which the blood to the recipient is caused to flow continuously.

I have found that one of the greatest obstacles to making successful blood transfusions is the coagulation of the blood due to inactivity of the latter during certain stages of the transfusion. Frequently, it becomes necessary to pass a certain amount of solution such as saline to, let us say, the recipient. At this time the valve 37 is moved for bringing the handle from the full line position to the dotted line position. This will place the tube 41 in communication with the tube 35 and will cut off the communication between the tube 40 and the tube 35. A continued reciprocation of the plungers will cause saline to flow to the recipient. The tube 41 may be inserted in any suitable receptacle containing saline.

A further important feature in connection with my invention is the fact that the handle 62 may be reversed. In other words, it may be operated from both sides of the device. When the handle is manipulated from the lower side shown in Figures 2 and 5, the direction of flow will be reversed. In many cases it is desirable to pass saline to the donor. Under such conditions, the valve 44 is manipulated for placing the tube 48 in communication with the tube 36. Continued manipulation of the handle will cause a flow of the liquid to the donor.

The device may be easily and quickly disassembled by merely loosening the thumb screw 8 and moving the member 5 slightly away from the barrel 20. At this time both barrels may be lifted from their supporting members and, by unscrewing the caps 16 and 17, the plungers may be pulled from the barrels. The handle 62 serves a double function in that it reverses the member 53 and at the same time serves as a grasping element

for reciprocating the plungers. The guides 51 and 52 shown in Figure 2 are arranged for permitting clamps to engage the base plate 1 at A and B, whereby the base may be rigidly secured upon any suitable supporting structure.

I claim:

1. A surgical instrument comprising a pair of hollow members having plunger means movably disposed therein, said plunger means being provided with a valve and passageways communicating with the valve and said hollow members, inlet and outlet liquid-conveying means communicating with said valve, said plunger means being arranged to create a suction within one of said hollow members whereby liquid will be caused to flow therein, said plunger being further arranged to cause a compression within the other of said tubular members for causing liquid therein to flow therefrom and into said outlet liquid-conveying means, said valve being arranged to place one of the hollow members in communication with the inlet liquid-conveying means when moved in one direction and the other of the hollow members in communication with the outlet liquid-conveying means, said valve being further arranged to reverse the communication between the inlet and outlet liquid-conveying means when said plunger means is moved in an opposite direction, a supporting member, and means mounted upon the latter for detachably supporting said hollow members. 35
2. A surgical instrument comprising a pair of hollow members having plunger means movably disposed therein, said plunger means being provided with a valve and passageways communicating with the valve and said hollow members, inlet and outlet liquid-conveying means communicating with said valve, said plunger means being arranged to create a suction within one of said hollow members whereby liquid will be caused to flow therein, said plunger being further arranged to cause a compression within the other of said tubular members for causing liquid therein to flow therefrom and into said outlet liquid-conveying means, said valve being arranged to place one of the hollow members in communication with the inlet liquid-conveying means when moved in one direction and the other of the hollow members in communication with the outlet liquid-conveying means, said valve being further arranged to reverse the communication between the inlet and outlet liquid-conveying means when said plunger means is moved in an opposite direction, a supporting member, and means mounted upon the latter for detachably supporting said hollow members. 40
3. A surgical instrument comprising a pair of hollow members having plunger means movably disposed therein, said plunger means being provided with a valve and passageways communicating with the valve and said hollow members, inlet and outlet liquid-conveying means communicating with said valve, said plunger means being arranged to create a suction within one of said hollow members whereby liquid will be caused to flow therein, said plunger being further arranged to cause a compression within the other of said tubular members for causing liquid therein to flow therefrom and into said outlet liquid-conveying means, said valve being arranged to place one of the hollow members in communication with the inlet liquid-conveying means when moved in one direction and the other of the hollow members in communication with the outlet liquid-conveying means, said valve being further arranged to reverse the communication between the inlet and outlet liquid-conveying means when said plunger means is moved in an opposite direction, a supporting member, and means mounted upon the latter for detachably supporting said hollow members, said plunger means having a portion engaging the base for guiding the plunger means. 45
4. A surgical instrument comprising a supporting structure, a valve having an inlet opening and an outlet opening, conduit means connected with the valve and communicating with said inlet and outlet openings, said valve comprising in part a movable member having a shiftable handle and recesses, and a pair of suction-compression devices mounted upon the supporting structure, each of said suction-compression devices comprising a pair of elements, one connected with the supporting structure and the other operatively connected with the valve and communicating with the same, one of the elements in each of the suction-compression devices being movable relatively with respect to its companion element, said valve being movable for operating said suction-compression devices for causing a continuous flow of a liquid through the valve in a predetermined direction, said handle assuming positions during the movement of the valve for indicating the direction of flow of the liquid through said valve, said handle being reversible for causing the liquid to flow in an opposite direction through the valve when manipulated in a shifted position. 50
5. A surgical instrument comprising a supporting structure, a valve having an inlet opening and an outlet opening, said valve comprising in part a plug having a pair of recesses and a shiftable handle, said valve being provided with feed openings, a pair of suction-compression devices, and conduits connected with the valve and communicating with the outlet and inlet openings, said conduits being provided with needle means for 55

connection with a donor and a recipient, each of said suction-compression devices comprising a pair of elements, one element of each of the devices being fixedly connected with the supporting structure and the remaining elements being operatively connected with the valve and communicating with said feed openings, one of the recesses in the movable part of the valve being arranged for placing one of the suction-compression devices in communication with the outlet opening and the other of said recesses being arranged for placing the other of the suction-compression devices in communication with the inlet opening during the movement of the valve in one direction, said recesses being shifted when the valve is moved in an opposite direction for changing the communication between the suction-compression devices and the valve for causing a continuous flow of liquid through the valve in a given direction, said handle being arranged for indicating the direction of flow through said valve.

6. A surgical instrument comprising a supporting structure, a valve having an inlet opening and an outlet opening, said valve comprising in part a plug having a pair of recesses and a shiftable handle, said valve being provided with feed openings, a pair of suction-compression devices, and conduits connected with the valve and communicating with the outlet and inlet openings, said conduits being provided with needle means for connection with a donor and a recipient, each of said suction-compression devices comprising a pair of elements, one element of each of the devices being fixedly connected with the supporting structure and the remaining elements being operatively connected with the valve and communicating with said feed openings one of the recesses in the movable part of the valve being arranged for placing one of the suction-compression devices in communication with the outlet opening and the other of said recesses being arranged for placing the other of the suction-compression devices in communication with the inlet opening during the movement of the valve in one direction, said recesses being shifted when the valve is moved in an opposite direction for changing the communication between the suction-compression devices and the valve for causing a continuous flow of liquid through the valve in a given direction, said handle being arranged for indicating the direction of flow through said valve, said handle being shiftable for reversing the action of the valve whereby the liquid will be caused to flow in an opposite direction.

7. A surgical instrument comprising a supporting structure, a valve having an inlet opening and an outlet opening, conduit means connected with the valve and communicating with said inlet and outlet openings, said valve comprising in part a movable member having a handle and recesses, and a pair of suction-compression devices mounted upon said supporting structure, each of said suction-compression devices comprising a pair of elements, one of said elements being operatively connected with the valve and movable with respect to the other of said elements, said valve being movable in a reciprocating manner for operating said suction-compression devices for causing a continuous flow of a liquid through the valve in a given direction, said handle assuming positions during the movement of the valve for indicating the direction of flow of the liquid through said valve.

8. A surgical instrument comprising a supporting structure, a valve having an inlet opening and an outlet opening, conduit means connected with the valve and communicating with said inlet and outlet openings, said valve comprising in part a movable member having a handle and recesses, and a pair of suction-compression devices mounted upon said supporting structure, each of said suction-compression devices comprising a pair of elements, one of said elements being operatively connected with the valve and movable with respect to the other of said elements, said valve being movable in a reciprocating manner for operating said suction-compression devices for causing a continuous flow of a liquid through the valve in a given direction, said handle assuming positions during the movement of the valve for indicating the direction of flow of the liquid through said valve.

9. A surgical instrument comprising a supporting structure, a valve having an inlet and an outlet opening, bearing means associated with the valve and arranged for riding upon said supporting structure, conduit means connected with the valve and communicating with said inlet and outlet openings, said valve comprising in part a movable member having a handle and recesses, and a pair of suction-compression devices mounted upon said supporting structure, each of said suction-compression devices comprising a pair of elements, one of said elements being operatively connected with the valve and movable with respect to the other of said elements, said valve being movable in a reciprocating manner for operating said suction-compression devices for causing a continuous flow of a liquid through the valve in a given direction, said handle assuming positions during the movement of the valve for indicating the direction of flow of the liquid through said valve, the position of said handle during the movement of the valve being also arranged for indicating the compression side of the valve.

10. A surgical instrument comprising two syringes detachably mounted in diametrical

- position upon a rigid support, each of said syringes comprising a pair of elements, one of said elements being operatively connected with a movable double channel valve by means of rigid tubular channels and movable with respect to the other of said elements, said valve so disposed that movement of the valve operates the syringes, simultaneously causing compression in one and suction in the other, said valve provided with ball bearings upon the surface contacting the rigid support, said valve provided with tubular orifices for attachment of intake and discharge conduits, said orifices diametrically disposed at ninety degrees from the orifices of the syringe channels, said valve provided with a movable core, said core having a projection operating in a quarter circle recess limiting its movement to a ninety degree arc, said core provided with two channels diametrically disposed and so arranged that at maximum rotation of the core in one direction one syringe channel is connected with the discharge orifice and the other syringe channel is connected with the intake orifice, said connection being reversed upon maximum rotation of the core in the opposite direction, said core provided with a handle for rotating the core within its ninety degree arc and moving the whole valve for operating the syringes, said handle so disposed as to indicate the direction of the flow of fluid through the instrument, said handle operating in a slot whereby its direction may be reversed thereby reversing the position of the valve core during operation, simultaneously reversing the direction of the flow of fluid through the device.
11. A surgical instrument comprising two syringes detachably mounted in diametrical position upon a rigid support, each of said syringes comprising a pair of elements, one of said elements being operatively connected with a movable valve by means of rigid tubular channels and movable with respect to the other of said elements, said valve so disposed that movement of the valve operates the syringes simultaneously causing compression in one and suction in the other, said valve provided with intake and discharge channels, and flexible conduits attached thereto, said valve having a movable member, said movable member provided with two channels so disposed as to connect the intake channel with one syringe, and the discharge channel with the other, said movable member having a handle for changing the position of the movable member changing the channel connections between the syringe channels and the intake and discharge channels, said valve channels so arranged with intake channel, syringe channels, and discharge channel that during operation fluid flows simultaneously in all channels of the device.
12. A surgical instrument comprising a supporting structure, a valve having an inlet
13. A surgical instrument comprising a supporting structure, a valve having an inlet and an outlet opening, bearing means associated with the valve and arranged for riding upon said supporting structure, conduit means connected with the valve and communicating with said inlet and outlet openings, said valve comprising in part a movable member having a handle and recesses, and a pair of suction-compression devices mounted upon said supporting structure, each of said suction-compression devices comprising a pair of elements, one of said elements being operatively connected with the valve and movable with respect to the other of said elements, said valve being movable in a reciprocatory manner for operating said suction-compression devices for causing a continuous flow of a liquid through the valve in a given direction.
14. A surgical instrument comprising a supporting structure, a valve having an inlet opening and an outlet opening, conduit means connected with the valve and communicating with said inlet and outlet openings, said valve comprising in part a movable member having a shiftable handle and recesses, and a pair of suction-compression devices mounted upon the supporting structure, each of said suction-compression devices comprising a pair of elements, one of said elements being operatively connected with the valve and movable with respect to the other of said elements, said valve being movable in a reciprocatory manner for operating said suction-compression devices for causing a continuous flow of a liquid through the valve in a given direction.
15. A surgical instrument comprising a supporting structure, a valve having an inlet opening and an outlet opening, conduit means connected with the valve and communicating with said inlet and outlet openings, said valve comprising in part a movable member having a shiftable handle and recesses, and a pair of

suction-compression devices mounted upon the supporting structure, each of said suction-compression devices comprising a pair of elements, one connected with the supporting structure and the other operatively connected with the valve and communicating with the same, one of the elements in each of the suction-compression devices being movable relatively with respect to its companion element, 10 said valve being movable for operating said suction-compression devices for causing a continuous flow of a liquid through the valve in a predetermined direction, said handle being reversible for causing the liquid to flow 15 in an opposite direction through the valve when manipulated in a shifted position, said handle being shiftable for reversing the action of the valve whereby the direction of flow is reversed.

16. A surgical instrument comprising a supporting structure, a valve having an inlet opening and an outlet opening, said valve comprising in part a plug having a pair of recesses and a shiftable handle, said valve 25 being provided with feed openings, a pair of suction-compression devices, and conduits connected with the valve and communicating with the outlet and inlet openings, said conduits being provided with needle means for 30 connection with a donor and a recipient, each of said suction-compression devices comprising a pair of elements, one element of each of the devices being fixedly connected with the supporting structure and the remaining 35 elements being operatively connected with the valve and communicating with said feed openings, one of the recesses in the movable part of the valve being arranged for placing one of the suction-compression devices in 40 communication with the outlet opening and the other of said recesses being arranged for placing the other of the suction-compression devices in communication with the inlet opening during the movement of the valve in one 45 direction, said recesses being shifted when the valve is moved in an opposite direction for changing the communication between the suction-compression devices and the valve for causing a continuous flow of liquid through 50 the valve in a given direction.

17. A surgical instrument comprising a supporting structure, a valve having an inlet opening and an outlet opening, said valve comprising in part a plug having a pair of recesses and a shiftable handle, said valve 55 being provided with feed openings, a pair of suction-compression devices, and conduits connected with the valve and communicating with the outlet and inlet openings, said conduits being provided with needle means for 60 connection with a donor and a recipient, each of said suction-compression devices comprising a pair of elements, one element of each of the devices being fixedly connected with the supporting structure and the remaining ele-

ments being operatively connected with the valve and communicating with said feed openings, one of the recesses in the movable part of the valve being arranged for placing one of the suction-compression devices in communication with the outlet opening and the other of said recesses being arranged for placing the other of the suction-compression devices in communication with the inlet opening during the movement of the valve in one 70 direction, said recesses being shifted when the valve is moved in an opposite direction for changing the communication between the suction-compression devices and the valve for causing a continuous flow of liquid through the valve in a given direction, said handle being shiftable for reversing the action of the valve whereby the liquid will be caused to flow in an opposite direction.

Signed at Rapid City, in the county of Pennington and State of South Dakota, this 31st day of October, A. D. one thousand nine hundred twenty-nine.
